UNDERGARMENT

Arthur R. Kneibler, Kenosha, Wis., assignor to
 Coopers Incorporated, Kenosha, Wis., a corpora-
 tion of Wisconsin

Application January 13, 1936, Serial No. 58,806
 Renewed December 27, 1938

8 Claims. (Cl. 2—224)

This invention relates to undergarments and more particularly to undergarments for men's wear.

The main objects of the invention are to provide an undergarment having body fitting characteristics not heretofore attained; to provide such a garment which may be manufactured economically and at low cost; to provide a snug fitting garment having certain body supporting effects but which has certain yielding abilities whereby comfort is attained; and in general it is the object of the invention to provide an improved garment of the type mentioned.

Other objects and advantages will be understood by reference to the following specification and accompanying drawing, wherein there is illustrated a garment embodying a selected form of the invention.

In the drawing:

Fig. 1 is a front elevation;

Fig. 2 is a fragmentary rear elevation;

Figs. 3, 4, 5 and 6 are sections on the lines 3—3, 4—4, 5—5 and 6—6, respectively of Fig. 1.

Referring now to the drawing, the improved garment therein illustrated is preferably formed of knitted textile material which is so arranged in the garment that the latter is materially extensible transversely, but substantially inextensible longitudinally. It is of course understood that such characteristics are incident to the ordinary extensibility of knitted material which is normally materially extensible in the direction transversely of its wales, but not materially extensible lengthwise of its wales. Hence, the wales of the material, as employed in the improved garment, are arranged to extend substantially vertically of the garment.

The garment comprises a main body part formed of front and back more or less triangular sections or portions 10 and 11, respectively, and right and left legs 12 and 13, respectively.

The triangular body-forming portions 10 and 11 are arranged with the upper edges 14 and 15, respectively, substantially in alignment and said edges are secured by stitching to a waist band 28, the latter being preferably made of elastic webbing.

The front triangular part 10 is preferably somewhat longer than the rear part 11 and said front part has its lower narrow portion provided with a transverse tuck 16 and its extreme end 17 joined to the extreme lower end 18 of the rear part 11 by stitching as indicated at 19. The stitching 19 is preferably of a form which serves

to materially limit the transverse extensibility of the crotch portion adjacent said seam.

The front body part 10 is preferably equipped with an angularly disposed fly or opening formed by angularly disposed overlapped fabric portions 20 and 21 which constitute portions of the front triangular part 10. The formation of this opening is substantially as described in my Patent No. 2,019,140, issued October 29, 1935.

It will be understood that the front triangular part 10 may practically be made either of two or three separate sections suitably united preferably along lines which are covered by tape strips such as indicated at 22 on the outside of the garment. As indicated in Fig. 1, one tape strip 22 extends vertically downwardly from the waist band of the garment a predetermined distance and then extends at an angle as indicated at 23 to the edge of the triangular front body part. The tape strip just referred to may serve to cover seams uniting either two or three body parts as will readily be perceived. The free edges of the overlapping parts 20 and 21 are also preferably bound by tape strips, as clearly indicated in Figs. 1 and 3. One convenient construction is to form the front body part of two separate pieces, making one piece serve for the lowermost crotch-including portion and the other piece to provide the upper portion including the two downwardly pointed portions into which the lower portion fits. It is not important just how the front body part is formed, but the foregoing is a practical arrangement.

The legs 12 and 13 of the garment have upper portions provided with upper edges 24 and 25, respectively, which are arranged substantially in alignment with the upper edges 14 and 15 of the front and back triangular body parts. As indicated, the upper edges 24 and 25 of the legs are connected with the upper edges 14 and 15 of the triangular parts and with the waist band 28.

The upper portions of the legs 12 and 13 also have front and back side edges 26 and 27, respectively, which are suitably stitched to the adjacent side edges of said front and back triangular parts. The stitching used for forming the seams between the side edges of the upper leg portions and the side edges of the triangular parts is preferably such that transverse stretching of the garment will not be materially prevented, although it may be of a character to reinforce the knitted material to prevent excessive stretching.

The lower portions of the legs are formed in

any suitable manner to constitute the desired leg lengths. The garment illustrated is of the ankle length variety, but it will be apparent that the leg length may be varied to suit the demands of the trade.

As an incident to the stitching together of the sides of the upper leg portions with the sides of the triangular front and back body portions, the tuck 16 is fastened or secured in its tuck form at its sides. Intermediate its sides, the tuck is free to be pulled out so that it provides excess material adapted to be drawn out when the garment is worn to provide the desired snug body fitting and supporting effect.

The tuck arrangement shown and described involves no complications in manufacturing the garment since it involves merely the provision of extra length in the front part 10 to form the tuck. Hence the described transverse tuck arrangement is preferred. However, other tuck or pleat arrangements may obviously be employed to secure the same yieldable structure which readily conforms the garment to the wearer so as to secure the desired snug body-fitting and supporting effect.

The elastic waist band member 28 is preferably of a comparatively rough or coarse weave which will tend to grip on other clothing under the waist band. The elastic waist band part 28 serves to adequately support the garment from the waist of the wearer.

By reason of the inextensible tape elements covering the seams in the front triangular part 10 and the free edges of the overlapping portions 20 and 21, a direct supporting effect for the crotch portion is obtained from the waist band. The direct supporting effect is somewhat more firm than the supporting effect which would be obtained by relying merely on the vertical inextensibility of the knitted fabric. To further amplify the supporting effect, the lower or crotch forming portion, i. e., the portion disposed below the inverted V formed by the angularly disposed tape portions, may be of double weight as clearly indicated in Figs. 3, 4 and 5. The double thickness of material is of course more resistant to stretching than a single thickness. Also the stitching joining the sides of said crotch-forming portion with the adjacent sides of the legs, being somewhat resistant to stretching tends to carry out the supporting effect of the inextensible tape strips described.

By reason of the described triangular downwardly extending form of the front and back panels 10 and 11 with their downwardly converging side edges and the described arrangement of the upper leg portions with their downwardly diverging side edges seamed to the adjacent converging edges of the front and back panels, the seams joining the front panel 10 with the respective side members approximately coincide with the groins of the wearer. This is a desirable feature in that it assists in conforming the garment to the body of the wearer in that the lines of the garment follow as nearly as practicable the lines of the body.

The garment described has been found to be exceptionally comfortable to wear, even though it conforms to the body with sufficient snugness to provide a supporting effect. The parts described embody comparatively simple shapes which are easy to cut out and handle in the production of the garment and little waste of material is occasioned in producing the said shapes.

Hence the garment may be made economically and at a low cost.

Changes in the described structure may be made without departing from the spirit of the invention, the scope of which should be determined by reference to the following claims, the same being construed as broadly as possible consistent with the state of the art.

I claim:

1. An undergarment having a crotch portion provided with a tuck extending transversely across the entire width of the crotch portion, said tuck being fastened by stitching along its side edges only and being free to be pulled out intermediate its side edges to conform to the body when the garment is worn, whereby a comfortable, yielding, supporting effect is obtained.

2. An undergarment comprising an endless elastic waist band adapted to support the garment from the waist of the wearer, front and back parts constituting front and back body portions of the garment, said parts having horizontally elongated upper edge portions joined to said elastic waist band and having lowermost portions narrowed in width and joined to form a narrow crotch portion of the garment, said narrow crotch portion being provided with a tuck extending transversely across the entire width of said narrow crotch portion, said tuck being fastened by stitching adjacent its side edges only and being free to be pulled out intermediate its side edges to conform to the body when the garment is worn, and to permit the garment to more or less adjust itself within certain limits to varying body lengths.

3. An undergarment of the class described made of elastic material, the garment being stretchable circumferentially and comprising a front panel tapering downwardly and having an end portion extending upwardly on the seat portion of the garment and of suitable width at the crotch to serve as a supporter, a back panel tapering downwardly and having its lower edge seamed to the end of the supporter portion, and a pair of side panels each having a body portion and an integral tubular leg, said body portions tapering upwardly and having the side edges thereof secured to the side edges of the front and back panels, the inner sides of said legs extending downwardly from the crotch.

4. An undergarment of the class described made of elastic material, the garment being stretchable circumferentially and comprising a front panel, a back panel and a pair of side panels; said front and back panels each tapering downwardly and one of said panels having an end portion passing through the crotch and seamed to the other above the crotch and of suitable width at the crotch to serve as a supporter; said side panels each having a body portion and an integral tubular leg, said body portions tapering upwardly and having the side edges thereof secured to the side edges of the front and back panels, the inner sides of said legs extending downwardly from said crotch.

5. A man's undergarment made of knitted material having substantially vertically extending, relatively non-extensible wales and which is stretchable circumferentially and adapted to fit snugly all parts of the body so that the material of the garment is under tension circumferentially while being worn, said undergarment having an elastic waist band which exerts a greater constrictive force than the knitted material of the garment and which serves to at least par-

5 tially support the garment in the vertical direction through the substantially inextensible wales of the knitted material employed; a front panel attached to said waistband and tapering downwardly toward the crotch and of suitable width at the crotch to serve as a masculine supporter; a rear panel extending upwardly and rearwardly from said crotch portion and connected at its upper edge to said waistband; and side panels forming lateral coverings for the trunk and 10 thighs between said front and back panels and connected thereto along their adjacent edges to form a complete garment, the lower portions of said side panels forming integral tubular legs extending downwardly from said crotch; the seams connecting the upper edges of said side panels to the front panels being relatively inextensible and being disposed along lines substantially coincident with the groins of the wearer, said 15 seams serving to resolve and transmit the lateral and vertical forces of the front and leg panels in the upper part of said garment so as to sustain and stretch transversely the material constituting the masculine supporting crotch of said garment, and serving with said waistband, at all 20 times to maintain said garment in snug body fitting relation on the wearer thereof.

6. A man's undergarment made of knitted material having substantially vertically extending, 30 relatively non-extensible wales and which is stretchable circumferentially and adapted to fit snugly all parts of the body so that the material of the garment is under tension circumferentially while being worn, said undergarment having an elastic waistband which exerts a greater 35 constrictive force than the knitted material of the garment and which serves to at least partially support the garment in the vertical direction through the substantially inextensible wales of the knitted material employed; a front panel 40 attached to said waistband and tapering downwardly toward the crotch and of suitable width at the crotch to serve as a masculine supporter; a rear panel extending upwardly and rearwardly from said crotch portion and connected at its upper edge to said waistband; and side panels forming lateral coverings for the trunk and 45 thighs between said front and back panels and connected thereto along their adjacent edges to form a complete garment, the lower portions of said side panels forming integral tubular legs extending downwardly from said crotch; the seams connecting the upper edges of said side panels to the front panels being relatively inextensible and being disposed along lines substantially coincident with the groins of the wearer, said 50 seams serving to resolve and transmit the lateral and vertical forces of the front and leg panels in the upper part of said garment so as to sustain and stretch transversely the material constituting the masculine supporting crotch of said garment, and serving with said waistband, at all 55 times to maintain said garment in snug body fitting relation on the wearer thereof; said undergarment further having a fly opening in said front panel so disposed as to be normally maintained closed by the pulling forces existing in 60 the garment itself when worn.

7. A man's undergarment made of knitted material having substantially vertically extending, 70 relatively non-extensible wales and which is stretchable circumferentially and adapted to fit snugly all parts of the body so that the material of the garment is under tension circumferentially while being worn, said undergarment hav-

5 ing an elastic waistband which exerts a greater constrictive force than the knitted material of the garment and which serves to at least partially support the garment in the vertical direction through the substantially inextensible wales of the knitted material employed; a front panel attached to said waistband and tapering downwardly toward the crotch and of suitable width at the crotch to serve as a masculine supporter; a rear panel extending upwardly and rearwardly from said crotch portion and connected at its upper edge to said waistband; and side panels forming lateral coverings for the trunk and 10 thighs between said front and back panels and connected thereto along their adjacent edges to form a complete garment, the lower portions of said side panels forming integral tubular legs extending downwardly from said crotch; the seams connecting the upper edges of said side panels to the front panels being relatively inextensible and being disposed along lines substantially coincident with the groins of the wearer, said 15 seams serving to resolve and transmit the lateral and vertical forces of the front and leg panels in the upper part of said garment so as to sustain and stretch transversely the material constituting the masculine supporting crotch of said garment, and serving with said 20 waistband, at all times to maintain said garment in snug body-fitting relation on the wearer thereof; said undergarment further having a fly opening in the front panel thereof disposed at an angle to the vertical and horizontal tension forces existing in said garment when worn, 25 whereby the edges of said fly opening are normally maintained closed by the resultant of said forces.

8. A man's undergarment made of knitted material having substantially vertically extending, 30 relatively non-extensible wales and which is stretchable circumferentially and adapted to fit snugly all parts of the body so that the material of the garment is under tension circumferentially while being worn, said undergarment having an elastic waistband which exerts a greater 35 constrictive force than the knitted material of the garment and which serves to at least partially support the garment in the vertical direction through the substantially inextensible wales of the knitted material employed; a front panel 40 attached to said waistband and tapering downwardly toward the crotch and of suitable width at the crotch to serve as a masculine supporter; a rear panel extending upwardly and rearwardly from said crotch portion and connected at its upper edge to said waistband; and side panels forming lateral coverings for the trunk and 45 thighs between said front and back panels and connected thereto along their adjacent edges to form a complete garment, the lower portions of said side panels forming integral tubular legs extending downwardly from said crotch; the 50 seams connecting the upper edges of said side panels to said front panels being disposed along lines substantially coincident with the groins of the wearer and being capable of exerting a pulling force sufficient to resolve and transmit the lateral and vertical forces of the front and leg panels in the upper part of said garment so as 55 to sustain and stretch transversely the material constituting the masculine supporting crotch of said garment, and with said waistband to maintain at all times said garment in snug body fitting relation on the wearer thereof.
